UNITED STATES PATENT OFFICE

ADOLPH ODDIE GOLDSTEIN, OF SANTA CRUZ, CALIFORNIA, ASSIGNOR TO SNO-KO INC.,
OF SANTA CRUZ, CALIFORNIA, A CORPORATION OF CALIFORNIA

DESIGN FOR A CASING FOR AN ICE-SHAVING MACHINE

Application filed January 11, 1930. Serial No. 34,097. Term of patent 7 years.

To all whom it may concern:

Be it known that I, ADOLPH ODDIE GOLDSTEIN, a citizen of the United States of America, residing at Santa Cruz, in the county of Santa Cruz and State of California, have invented a new, original, and ornamental Design for a Casing for an Ice-Shaving Machine, of which the following is a specification, reference being had to the accompanying drawing, forming a part thereof.

The figure is a perspective view of the article showing my new design.

The four corners of the machine as shown in the figure of the drawing, are identical, with the corner shown in the foreground thereof.

I claim:

The ornamental design for a casing for an ice-shaving machine, substantially as shown and described.

ADOLPH ODDIE GOLDSTEIN.
